TRAFFIC SIGNAL

Howard E. Miller, Douglas County Court House,
Tuscola, Ill.

Filed Oct. 15, 1965, Ser. No. 87,517

Term of patent 14 years

(Cl. D72—1)

FIG. 1 is a front elevational view of the traffic signal, showing my new design;

FIG. 2 is a side elevational view;

FIG. 3 is a rear elevational view; and

FIG. 4 is a top plan view.

The broken line representation of a support pole in FIGS. 1, 2, and 3 is for purposes of illustration only.

I claim:

The ornamental design for a traffic signal, as shown and described.
